United States Patent Office.

GEORGE SCOTT, OF LOUISVILLE, KENTUCKY.

Letters Patent No. 91,775, dated June 22, 1869.

IMPROVED ELEVATOR

The Schedule referred to in these Letters Patent and making part of the same.

To all whom it may concern:

Be it known that I, GEORGE SCOTT, of Louisville, county of Jefferson, State of Kentucky, have invented a new and improved Elevator; and I hereby declare the following to be a full, clear, and exact description thereof, which will enable those skilled in the art to make and use the same, reference being had to the accompanying drawings, making a part of this specification, in which—

Figure 1 is a perspective view.

Figure 2 is a top view of safety-clamp or clamping lever.

Figures 3 and 4 are top views of other safety-clamps, which may be used instead of the one shown in fig. 2.

Similar letters of reference indicate corresponding parts.

My invention relates to that class of elevators which performs its function by means of a sliding platform, hoisted or lowered with the aid of a cord and pulleys.

It consists in providing a band, lever, and safety-clamps, in connection with said platform, which, in case the elevating-rope should break, effectually secure the platform to the sides of the frame, so as to prevent its fall, and in an improved construction and arrangement of its several parts, as will be hereinafter more fully described.

In the drawings—

A is the frame, the uprights of which are cleated on their outer sides.

A¹ are vertical slots in the cross-piece of the frame, in the sides of which the pulleys have their bearings.

The hoisting-cord is secured to the frame at the eye-bolt A².

B are common pulleys, double grooved.

C is the platform, which is of ordinary construction, excepting the horizontal groove C² across the face of its slides C¹, to admit the jaws of the clamps, and two vertical grooves, C³, at the centre of the beam, into which fits an iron or other band, D.

D is an iron or other band, which is made large enough to permit it to slide up and down on the beam, and in the top of which the hoisting-rope D¹ is fastened.

D² is a leather strap, passed around the ends of the safety-clamps, the ends of which are drawn through the lower end of the band D.

E is a lever, which is pivoted to the beam of the platform at e. Said lever has a forked end, which passes under the beam and over the ends of the clamps.

E¹ is a rope or cord, secured to the upper end of the lever, and carrying a balance-weight, E².

F are safety-clamps, which are composed of a rigid

arm and jaws. These jaws are nearly square, and clasp the cleats on the uprights. Where the arm passes through the slide, and on its upper edge, a groove of sufficient width and depth is made, to allow it to play freely in the slot in which it works.

F¹ is a safety-clamp, having loose jaws, similar in shape to those of F. These jaws are riveted to a slightly curved arm at f. This arm has a cam-shaped end.

F² is a safety-clamp, composed of a gently curved arm, having a T-piece for its head. When this clamp is used, the interior surfaces of the uprights of the frame must be grooved in the form of a T, to receive its head.

The operation of my invention is as follows:

The platform being at rest, with the leather strap D² passed far enough through the iron band to maintain the arms of the clamps in a horizontal position, a sufficient pull on the rope D¹ will hoist the platform on the uprights of the frame. When it has reached the desired height, pass the disengaged end of the rope D¹ through the eye-bolt A², where it may be securely fastened.

In the event of the rope D¹ breaking, the fall of the platform, with the force of the balance-weight E², by means of the rope E¹, is sufficient to raise the upper arm of the lever E, which presses its hooked portion upon the ends of the clamps. This brings two of the sharp edges of the clamp-jaws into such close contact with the uprights that it is impossible for the platform to descend.

Having thus described the nature and operation of my invention,

What I claim as new, and desire to secure by Letters Patent, is—

1. The clamping-levers F, and their combination with the uprights C¹, and the upright portions of the frame A, constructed substantially as shown and described.

2. The combination of the lever E and the clamping-lever F, substantially as shown and described.

3. The combination of the lever E, cord or chain E¹ and balance-weight E², substantially as shown and described.

4. The arrangement of the band D and strap D², with reference to the clamping-levers F, substantially as shown and described.

In testimony whereof, I have signed my name to this specification, in the presence of two subscribing witnesses.

GEORGE SCOTT.
